UNITED STATES PATENT OFFICE.

FRANCIS A. FLANEGIN, OF CHAUTAUQUA, NEW YORK.

METHOD OF CLEANING OIL-WELLS.

949,567.

Specification of Letters Patent. Patented Feb. 15, 1910.

Application filed March 30, 1908. Serial No. 424,021.

To all whom it may concern:

Be it known that I, FRANCIS A. FLANE-
GIN, a citizen of the United States, residing
at Chautauqua, in the county of Chautauqua
5 and State of New York, have invented cer-
tain new and useful Improvements in Meth-
ods of Cleaning Oil-WellS, of which the fol-
lowing, taken in connection with the accom-
panying drawings, is a full, clear, and exact
10 description.

The invention relates to oil wells and has
for its object the removal of the paraffin,
gypsum and other deposits which accumu-
late in the crevices of the oil bearing portion
15 of the well.

In order to increase the flow of oil wells
as is well known, it has been the practice for
years to explode a charge of nitro-glycerin
20 or some other explosive in the oil bearing
portion of the well, thereby greatly increas-
ing the capacity of the crevices by separa-
tion. These crevices are closed by the ac-
cumulation of paraffin, gypsum and other
25 deposits from the oil which become exceed-
ingly hard, in some instances, coating the
entire wall of the shot cavity. The easiest
way to remove this coating from the walls
of the shot cavity has been to heat liquid
30 within the well to a boiling point, thereby
producing a strong ebullition of the liquid,
dissolving the paraffin and opening the crev-
ices. Heretofore, however, oil producers
have never allowed the injection of a quan-
35 tity of water in the well even to clean it
since the water was liable to curdle the oil
and entirely stop the flow of the oil. As is
well known, oil wells are piped at great ex-
pense in order to shut the fresh water out of
40 the wells. It has been found that water
treated with salt, borax, ammonium-hydrate
and the like, does not curdle the oil, that
ebullition of the liquid is produced under a
covering of oil with fewer heat units than
45 when no covering is used, and that the ebul-
lition of said liquids aids greatly in cleans-
ing the walls of the shot cavity. It is also
a well established fact throughout the oil
bearing region and particularly with oil re-
50 finers that the ebullition of rock oil or crude
petroleum occurs at a higher temperature
than water which boils at 212 degrees Fahr-
enheit. Thus for example, crude petro-
leum from the Tiona fields in Pennsylvania,
55 which is one of the lighter crude oils, reaches
the point of ebullition at about 230 degrees

F. It is apparent that a heavier crude oil
would need a higher degree of heat.

My method of treating wells therefore,
consists in bailing the well clean, or nearly
so, then placing therein a sufficient amount 60
of ammoniated, borated, salt, or fresh water,
to fill the well to a point above the oil bear-
ing rock, which point is usually indicated
by the shot cavity, then placing above the
water a sufficient amount of oleous liquid to 65
form a liquid packing or covering to hold
the heat in the water, and then inserting a
heater through the oleous liquid into the
water to heat the same.

It has been practically demonstrated that 70
ammoniated water may be used without a
packing of oleous liquid and may be raised
to the boiling point or point of ebullition
with a considerable reduction of heat units
from the amount required for fresh water; 75
but by the use of the oleous packing over the
ammoniated liquid a much greater reduction
of required heat units is attained. Thus the
ammoniated aqueous liquid with a packing
of oleous liquid requires only about one- 80
third to one-half the number of heat units
which fresh water would require. The prac-
tical demonstrations made also show that
the use of ammonia is highly preferable to
85 other salines such as borax or salt, since the
ammoniated water boils at a much lower
temperature. The cleansing effect of the
ammonia also is well known. The use of
any of these forms of saline treated waters
or fresh water with such a covering of oil 90
is much more advantageous than the use of
said liquids without such a covering, for the
following reasons: It has been demonstrated
that the oleous liquid holds the heat down by
absorbing the steam bubbles as they rise up 95
through the water underneath. The oil thus
acts as a resilient or adaptable packing, cov-
ering or plug for the water which prevents
the escape of the heat from the water up into
the bore of the well; that is, the oil will move 100
upward as the water expands from the heat,
yet continues to absorb the steam bubbles as
they rise, thereby inclosing the water almost
as in a vacuum and preventing the escape of
the heat up the well bore. This prevents the 105
heating of the casing and consequent damage
from the expansion of the heated casing.
Wells have been renewed by the use of
steam or use of heat by other means, which
caused the expansion of the casing to such a 110

degree that the casing had to be entirely withdrawn and repacked. By my simple packing of oil over the water, all such danger is overcome and at the same time a great saving of heat units is attained, thereby cheapening the process of cleaning the well.

As soon as a sufficient degree of heat and ebullition of the liquid is attained for the 10 cleansing of the crevices of the shot cavity, all the liquids are bailed from the well and the sand pump is used to remove all the solid substances which may have been dislodged in the process.

15 Since my process attains its purpose by the use of the minimum amount of heat units, one of my objects is to provide as simple a means as possible for heating the saline treated water and causing its ebullition beneath the packing of oil.

In the drawings Figure 1 is a sectional view of a portion of the lower end of an oil well including the shot cavity and showing the oil bearing sand, also showing a sectional 25 view of my heater within the same, the shot cavity being filled with water with the covering or packing of oil above the same. Fig. 2 is a side elevation of the heater. Fig. 3 is a side elevation of the metal billets placed 30 one above another as placed within the heater casing.

Similar numerals refer to corresponding parts in the several views.

The heater consists of a casing or jacket indicated by the numeral 10, which jacket is 35 preferably formed of a tube of the desired length, which is somewhat less in diameter than the casing of the oil well so that the tube may be easily raised and lowered with- 40 in the bore of the well.

The casing 10 has a long bail 11 at its upper end for attaching the line 12. The long bail allows of the insertion of the metal billets 13 within the casing 10. The lower 45 end of the tubular casing 10 is closed by means of a screw cap 14 which has a central opening 15 in the bottom.

A valve seat 16 is provided around the upper side of hole 15 and a valve 17 fits on 50 to valve seat 16 within cap 14. Valve 17 has a stem 18 extending therefrom and ending in an enlarged lower end 19. Stem 18 is made sufficiently long to keep end 19 from closing the opening 15 in the bottom of the 55 casing. It is apparent that the valve 17 will strike pin 22 and thereby prevent the valve stem from rising a sufficient distance to close the orifice 15.

A sufficient number of metal bars 13 are 60 provided to fill the tubular casing 10. Bars 13 are of sufficiently less diameter than the tubular casing 10 to allow the fluid to flow up around the sides of the bars and out of the top of the heater in order to produce the 65 flow and ebullition of the fluid desired.

Bars 13 are preferably formed with holes 23 in the sides so that they may be easily and positively engaged by a suitable pair of tongs having jaws shaped to engage said holes. Also the lower ends 20 are slightly 70 cone-shaped and the upper ends 21 are hollowed out similar to said cone-shaped lower ends so that as the metal billets are dropped one upon another they center themselves upon one another and thus keep the way 75 clear between the sides of the same and the inner side of the casing 10.

In using this simple form of heater the bars 13 are heated to an intense degree of heat and then lowered into the casing by 80 means of a suitable pair of tongs, which casing is preferably hung in the mouth of the well before the heated bars are dropped into the same. The bars will rest upon the cross-wise pin 22 and as soon as the casing is 85 filled it may be rapidly lowered by suitable means into the shot cavity. Before lowering the heater, a sufficient amount of water is placed in the well to fill the shot cavity 24 and a packing of oil 25 is placed over the 90 same. The heater is then lowered quickly, the enlarged lower end 19 of the valve stem 18 is sufficiently heavy to close the heater valve 17 while the casing 10 is passing down through the bore of the well and the oil 95 packing and water so that the heat is retained by the metal bars until the shot cavity is reached, then the lower end 19 strikes the deposit 26 which always accumulates in the pocket at the bottom of the well and pressing up on valve 17 allows the liquid to 100 rush up through opening 15 around the heated metal billets 13. The heated billets 13 within the tubular casing 10 create steam which rises through the liquid thereby 105 creating ebullition and circulation of the fluids.

It is apparent that if the weight 19 of the valve 17 is sufficiently light to allow the air or liquid to raise the same as the casing rapidly descends to the bottom of the well, thereby allowing the air or liquid in the well to flow around the heated billets, they would be cooled long before they reached the shot cavity. It is also obvious that liquid running into the casing 10 from the top as it 110 passes down through the liquid will be raised to the boiling point and will prevent other liquid from flowing in and thus the heat of the billets 13 will be retained until 115 the shot cavity or oil-bearing portion of the well is reached.

It is apparent that this simple heater will heat a sufficient quantity of water to fill the shot cavity in a very short space of time and with a minimum amount of heat when packed with oil, as above described, and also that the heater can pass down through the oil packing without obstruction. Should one insertion of the heater be insufficient to 120

125 130

heat the water to the desired temperature, it can be drawn up and recharged with fresh heated irons and reinserted as many times as desired. It is also obvious that where 5 saline compounds such as borax or ammonia can not be obtained, the difference in the number of heat units necessary to produce ebullition in oil and fresh water will still give a great advantage over the use of fresh 10 water by itself. It is also apparent that the oil adjusts itself to the form of the well bore or shot cavity and thereby shows that a liquid packing forms the only sure packing for this purpose. This has been repeatedly demon- 15 strated in removing the liquids from the wells. After cleaning the same it has been found that the temperature of the oil packing would allow of the insertion of the hand without any inconvenience, it being at such 20 a low temperature, whereas the water under the oil was heated to a scalding temperature, which immediately produced a high degree of vaporation when exposed to the air, thus giving a very clear demonstration of the 25 value of my process.

I claim as new:—

1. The method of cleaning oil wells, which consists in supplying two liquids to the well, one of which floats upon the other 30 to form a covering for the lower liquid, and heating the lower liquid.

2. The method of cleaning oil wells which consists in filling the well to a point above the oil bearing rock with an aqueous 35 liquid, then supplying oleous liquid to form a covering for said aqueous liquid, and applying heat to the lower liquid.

3. The method of cleaning oil wells, which consists in removing the contents of 40 the well, filling the well to a point above the oil bearing rock with an aqueous liquid, supplying an oleous liquid to cover the aqueous liquid, inserting a heater in said aqueous liquid, and then removing the heater 45 and the liquid from the well.

4. The method of cleaning oil wells,

which consists in removing the contents of the well, filling the well to a point above the oil bearing rock with a paraffin solvent, supplying an oleous liquid to cover the solvent, inserting a heater in said solvent to heat the same beneath the oleous liquid, and then removing the heater and the liquids from the well. 50

5. The method of cleaning oil wells, 55 which consists in removing the contents of the well, filling the lower portion of the well with an ammoniated aqueous liquid, heating said liquid and then removing the liquid from the well. 60

6. The method of cleaning oil wells, which consists in removing the contents of the well, filling the well to a point above the oil-bearing rock with an ammoniated aqueous liquid, covering said liquid with an 65 oleous liquid, heating the ammoniated liquid beneath the oleous liquid, and then removing the liquids from the well.

7. The method of cleaning oil wells, 70 which consists in removing the liquid contents of the well, filling the shot cavity of the well with an ammoniated aqueous liquid, covering said liquid with petroleum oil, heating said ammoniated liquid beneath said oil, and then removing the liquids from the 75 well.

8. The method of cleaning oil wells which consists in removing the liquid from the well, filling the well to a point above the oil-bearing rock with a paraffin solvent, covering said solvent with an oleous liquid, heating said solvent beneath the oleous liquid and agitating the same, and then removing the liquid contents from the well. 80

In testimony whereof I have signed my 85 name to this specification in the presence of two subscribing witnesses.
